CLAIM

We claim the ornamental design for a shopping cart disinfection machine, as shown and described.

DESCRIPTION

FIG. 1 is a perspective view from a first end of a shopping cart disinfection machine.

FIG. 2 is a side view of the system from a first side.

FIG. 3 is a side view of the system from a second side opposite the first side.

FIG. 4 is an end view of the system from a second end opposite the first end.

FIG. 5 is an end view of the system from the first end.

FIG. 6 is a top view of the system; and,

FIG. 7 is a perspective view thereof. The broken line showing of shopping carts in FIG. 7 depicts environmental subject matter and forms no part of the claimed design.
